UNITED STATES PATENT OFFICE.

NILS M. ROSENDAHL, OF WINTHROP HARBOR, ILLINOIS, ASSIGNOR TO FREDERICK C. AUSTIN, OF CHICAGO, ILLINOIS.

MACHINE FOR MAKING ASPHALTIC OR SIMILAR MIXTURES.

1,293,937.

Specification of Letters Patent.

Patented Feb. 11, 1919.

Application filed April 6, 1914. Serial No. 829,748.

To all whom it may concern:

Be it known that I, NILS M. ROSENDAHL, a citizen of the United States of America, and resident of Winthrop Harbor, Lake 5 county, Illinois, have invented a certain new and useful Improvement in Machines for Making Asphaltic or Similar Mixtures, of which the following is a specification.

My invention relates to machines for making asphaltic or other similar mixtures, and more particularly to machines of this kind which are of a portable nature, such as those employed in paving streets, and more especially to those which are provided with 15 means for heating all of the materials before they are combined in the required proportions to form the desired mixture.

Generally stated, the object of my invention is to provide a novel and highly efficient machine of this general character, having the elements thereof constructed and arranged in a more compact and satisfactory manner than heretofore.

Special objects are to provide a better and 25 more efficient construction and arrangement of the apparatus for heating the sand, crushed rock, gravel or other loose materials ordinarily employed in the making of asphaltic mixtures of this character; to provide, in conjunction with the means for heating the asphalt and other materials, a novel and efficient form of device for thoroughly mixing or combining said materials; to provide an improved construction and arrangement for transferring the loose materials from the heating apparatus to the mixing device, of such character that the materials discharged from said apparatus 35 may be returned thereto, if not properly heated or dried, or if the mixing device is in operation and requires more time in which to mix the batch; to provide a novel construction and arrangement whereby the heated air and hot gases are taken through the said apparatus, by a suction fan or blower, for the purpose of drawing off the dust and moisture, thereby leaving the said loose materials in perfectly dry and dustless condition; and to provide certain details 45 and combinations and features of construction tending to increase the general efficiency and desirability of a preparing and mixing machine of this particular character.

55 To these and other useful ends my inven-

tion consists in matters hereinafter set forth and claimed.

In the accompanying drawings:

Figures 1 and 2, taken together, represent a side elevation of a preparing and mixing 60 machine embodying the principles of my invention, showing the same more or less in longitudinal section.

Fig. 3 is a transverse section on line 3—3 in Fig. 1.

Fig. 4 is a transverse section on line 4—4 in Fig. 2.

Fig. 5 is a transverse section on line 5—5 in Fig. 2.

Fig. 6 is a detail section, on a larger scale, 70 on line 6—6 in Fig. 2, illustrating the construction of the mixing device, and showing certain portions thereof broken away for convenience of illustration.

Fig. 7 is an end view of the structure 75 shown in Fig. 6, showing the same partially in transverse section, and illustrating the rack and pinion mechanism by which the mixing receptacle is tilted into dumping position upon the completion of the 80 batch of mixture.

Fig. 8 is a section on line 8—8 in Fig. 6.

Fig. 9 is a detail view showing the arrangement whereby steam or other fluid pressure is employed for transferring the 85 semi-liquid or melted asphalt from the tank or reservoir to the mixing receptacle.

As thus illustrated, my invention comprises a body or platform A supported on wheels B of any suitable character, the machine being of a portable nature and adapted to be drawn from place to place. The asphalt is contained in a tank or reservoir C which is suitably supported on the said platform or body, and the lower surface of 90 which is formed by a concave wall c, whereby a space c¹ is formed below. In this space an outer cylinder D is disposed in horizontal position, being provided at one end with a flange d¹ which travels on rollers d¹, and at 95 its other end with a similar flange d² which travels on rollers d², whereby said cylinder may be rotated about a horizontal axis. For this purpose the receiving end of said cylinder is provided with gear teeth d³ operated by a belt connection from the drive shaft E supported in any suitable manner at one side of the machine. Two other cylinders, F and G, are disposed within the cylinder 100

D, concentrically and with space between, the cylinder F being secured at one end to the discharge end of the cylinder D, and the cylinder G being secured at its opposite end to the receiving end of the cylinder D, in the manner shown more clearly in Fig. 2. The loose materials, such as sand, crushed rock or gravel are discharged from the spout H through the inlet opening d^2 and into the end of the innermost cylinder G, which latter is provided internally with obliquely arranged blades g that serve to gradually move the materials to the right and discharge them from the other end of said cylinder. The cylinder F is provided internally with similar blades f , but as these are disposed at a different angle, the materials now move to the left in the rotating cylinder F and are discharged from the end thereof. The cylinder D is provided internally with blades d^6 disposed at the same angle as the blades g , whereby the materials are caused to move to the right in this cylinder, and are finally discharged from the openings d^7 in the end of said outer cylinder. These cylinders, and also the asphalt tank or reservoir above, are heated by gas burners 1, of any suitable character, disposed below the said cylinders. With this construction and arrangement, the loose materials, such as sand, crushed rock or gravel, are caused to move back and forth, from one cylinder to the other, and are not allowed to escape until they are thoroughly heated and dried. By this back and forth movement of the materials, in the manner shown and described, the length of the machine is considerably reduced, notwithstanding the fact that the amount of travel these materials are compelled to undergo is actually of some distance and entirely sufficient for insuring proper heating and drying of the materials before they are discharged from the last cylinder or drum.

Figs. 1 and 3 show the means for conveying and delivering the sand or other loose materials to the spout H, the construction and operation thereof being as follows:—The spout H forms an outlet for the bottom of the hopper h and is provided with a controlling valve h^1 which is opened and closed by a handle h^2 having suitable connection therewith. A vertically disposed conveyer or elevator J is disposed at one side of said hopper, as shown in Fig. 3, and has its upper end connected thereto by a spout j , the lower end of said elevator having a receiving end portion j^2 into which the sand or other material is shoveled. This elevator can be of any suitable character, such as those shown in Fig. 4, and serves to carry the sand or other materials upward to the spout j , from which latter the said materials are then discharged into said hopper. A housing K is disposed between the

said hopper and elevator, and is suitably connected with the intake k thereof, shown in Fig. 2, whereby said housing communicates with the interior of the rotary cylinders. The said housing has an outlet provided with a suction fan or blower k^1 , operated in any suitable manner, whereby the heated air and hot gases produced by the burners 1 are drawn through the cylinders and into said housing K and then discharged by said fan or blower into the atmosphere. This, it will be understood, serves to draw all of the dust and moisture from the interior of the cylinders, leaving the sand or other materials therein perfectly clean and dry—that is to say, in a highly heated and dustless condition.

The devices for combining and mixing the materials in the proper or desired proportions are as follows:—A measuring receptacle L is disposed above the mixing receptacle M, within the housing N, and these are constructed and operated in the following manner:—Said receptacle L has its upper side provided with an inlet opening l , and has its ends provided with trunnions l^1 , of any suitable character, supported on horizontal bars l^2 , and a handle l^3 is applied to one end of this tilting or oscillating receptacle. The receptacle M is also supported in trunnion bearings m and m^1 , as shown in Fig. 6, being provided at one end with a pinion m^2 which is engaged by a rack m^3 , whereby said receptacle may be tilted about a horizontal axis to dump or discharge the batch of mixture. The said receptacle is provided with double walls providing a space m^4 to which steam is admitted through the hub openings m^5 from the supply pipe m^6 , or in any other suitable manner. The rotary shaft m^7 extends through the trunnions of said receptacle, being supported thereby, and is provided with radially extending long and short blades m^8 and m^9 , it being observed that these blades are disposed in pairs, each pair being formed by a long and short blade, and the members of each pair extending radially at opposite sides of the shaft. It will also be seen that the members of each pair of blades are arranged at an angle and disposed in the same oblique plane, whereby the two blades which form a pair operate in opposite directions—that is to say, one blade pushes the materials along the shaft in one direction, like the blade of a propeller wheel, and the other blade of the same pair pushes the materials along the shaft in the opposite direction. In this way, and by reason of the difference in length of the members of each pair of blades, a peculiar effect is produced on the melted asphalt in the receptacle M, and on the other materials to be combined therewith, the general effect being a very complete breaking up and thorough

mixing together of the different materials—that is to say, the blades cut the mass here and there and turn it over, so to speak, and in this way effect a very thorough and even mixing together of the different materials. It will be understood that the shaft m' can be rotated by any suitable means.

The asphalt is conducted from the tank or reservoir through a pipe or pipes to the

- 10 receptacle M in any suitable manner. For example, and with a view to avoiding the use of pumps for this purpose, the asphalt can be conducted from the reservoir through a pipe O to a small trap or reservoir P, and 15 then through a pipe p to said mixing receptacle; and after the said trap or reservoir P is full, or after it contains the required amount, a three-way valve o, of any suitable character, disposed in the pipe O can then be turned 20 to shut off the flow of asphalt, and to admit steam from the pipe o¹; and the steam pressure thus admitted to the top of the trap or reservoir P then forces the contents thereof 25 into the pipe p and from there into the mixing receptacle. Thus the steam keeps the asphalt hot and in flowing condition and forces the same along to the point where the mixture is to be effected.

The means for transferring the loose materials from the heating apparatus, after the same are discharged from the openings d⁷, is as follows:—A chute or spout Q receives the said materials and conveys them to the lower end of the elevator or vertically, disposed conveyor R, and from the top of the latter the materials are then discharged into a storage chamber S having a sloping bottom s by which the materials are then conveyed through a bottom opening to the lower end of the similar elevator T, which latter has its upper end provided with a spout t whereby the materials are then finally discharged into the measuring receptacle L, which latter is then tilted over to discharge its contents into the mixing receptacle below. It will be seen, however, that a valve U is provided near the top of the elevator R, and that by moving this valve into the position shown in dotted lines in Fig. 4, by any suitable operating means, the materials will then be deflected into the spout or chute V which leads to the inlet opening W of the cylinder F, whereby the materials are returned for further treatment in the rotating drums or cylinders comprised in the heating and drying apparatus. Thus, and in this way, the loose materials can be diverted back into the said apparatus, if found to be not properly heated or dried, or if the mixing receptacle M is full and more time is required for mixing the batch, or if the storage chamber is full. This, it will be seen, is accomplished without stopping the rotation of the cylinders D, F and G and without stopping the operation of the elevators R and T,

the preparing and drying apparatus being permitted to run continuously and without interruption. While the materials are passing through chute V to the rotary drier, the storage chamber S may be feeding its contents to the lower end of elevator T, so that the mixing operation will not be interrupted. When the elevator T is stopped after the measuring receptacle is filled, the elevator R continues to discharge into said storage 75 chamber. As this chamber S is close to the heat, the materials therein are kept hot.

From the foregoing it will be seen that I provide a preparing and mixing machine in which the various elements and instrumentalities are very compact and conveniently arranged, the materials being given the desired amount of treatment, while passing through the heated area, without the necessity of undesirably lengthening the machine. 80 It will also be seen that means are provided for efficiently and properly combining the materials, it being understood that the skill and judgment of the operator will be exercised more or less in the running of the machine. For example, and with respect to the most efficient operation of the blades in the receptacle M, the latter should be filled to a point a little above the shaft m' , in order to obtain the best results. As to the 85 proper heating and drying of the loose materials, the operator or attendant will observe the same, as they are discharged from the rotary heating apparatus, and will guide them into the mixing machine or back into 90 the said apparatus depending upon their condition. The drier is covered by my pending application, Serial No. 870,444.

What I claim as my invention is:

1. A machine for making asphaltic mixtures, comprising means for heating the asphalt or similar substance, apparatus whereby the same heat is employed for raising the temperature of the other or loose materials, such as sand, crushed rock or gravel, 105 instrumentalities for combining said materials in the desired proportions and having devices for mixing and discharging the same in batches, means to feed the asphalt to said devices, an elevator and a hopper for feeding 110 the materials to said apparatus, an elevator for raising the materials from said apparatus, and said instrumentalities having provisions whereby the loose materials are returned to said apparatus, if necessary, or 115 120 are conveyed to said devices.

2. A machine for making asphaltic mixtures, comprising means for heating the asphalt or similar substance, apparatus whereby the same heat is employed for raising the 125 temperature of the other or loose materials, such as sand, crushed rock or gravel, instrumentalities for combining said materials in the desired proportions and having devices for mixing and discharging the same in 130

- batches, means to feed the asphalt to said devices, a pair of elevators for transferring the loose materials from said apparatus to said devices, the first elevator delivering from its upper end to the lower end of the second elevator, and means for cutting out the second elevator to return the loose materials to said apparatus from the upper end of said first elevator.
- 5 3. A machine for making asphaltic mixtures, comprising means for heating the asphalt or similar substance, apparatus whereby the same heat is employed for raising the temperature of the other or loose materials, such as sand, crushed rock or gravel, instrumentalities for combining said materials in the desired proportions and having devices for mixing and discharging the same in batches, means to feed the asphalt to said devices, and means whereby the loose materials discharged from said apparatus are returned thereto, if necessary, without being mixed with the asphalt, said apparatus having an inlet at its discharge end for receiving the returned materials.
- 10 4. A machine for making asphaltic mixtures, comprising means for heating the asphalt or similar substance, apparatus whereby the same heat is employed for raising the temperature of the other or loose materials, such as sand, crushed rock or gravel, and instrumentalities for combining said materials with the asphalt in the desired proportions and having devices for mixing and discharging the same in batches, means to feed the asphalt to said devices, said apparatus having axial inlet openings at both ends thereof and an outlet at only one end, means to carry the loose material away from said outlet and back to one of said inlets, when necessary, thereby preventing the loose material from reaching the place where the mixture is formed, and means subject to said heat to convey the materials from said apparatus to said instrumentalities.
- 15 5. A machine for making asphaltic mixtures, comprising means for heating the asphalt or similar substance, apparatus whereby the same heat is employed for raising the temperature of the other or loose materials, such as sand, crushed rock or gravel, instrumentalities for combining said materials with the asphalt in the desired proportions and having devices for mixing and discharging the same in batches, means to feed the asphalt to said devices, said devices including a mixing receptacle, means for heating said receptacle, means for feeding the asphalt to said receptacle, a member for delivering the other materials to said receptacle in batches, and means whereby the loose materials discharged from said apparatus are carried upward and then returned downward thereto, before reaching said member, while the said receptacle is mixing a batch, and without stopping the operation of said apparatus.
- 20 6. A machine for making asphaltic mixtures, comprising means for heating the asphalt or similar substance, apparatus whereby the same heat is employed for drying and raising the temperature of the other or loose materials, such as sand, crushed rock or gravel, and instrumentalities for combining said materials with the asphalt in the desired proportions and having devices for mixing and discharging the same in batches, means to feed the asphalt to said devices, said devices including a batch mixing receptacle, and said machine having means whereby the loose dry materials discharged from said apparatus are carried upward and then returned downward thereto, if not in proper condition, or if necessary to give said receptacle sufficient time to mix the batch.
- 25 7. A machine for making asphaltic mixtures, comprising a drying apparatus, a mixer, an elevator for raising the loose materials from said apparatus, a hopper for receiving the materials from said apparatus and automatically feeding the same to the lower end of said elevator, a second elevator disposed at one side of said first elevator, a chamber forming a hopper for receiving the materials from the top of said first elevator, said chamber being adapted to store a quantity of the materials and having a bottom opening for feeding the materials to the lower end of the second elevator, means to return the materials to said apparatus when desired, a spout leading from the top of said second elevator to the mixer, a spout leading downward from the top of said first elevator to said apparatus, and a valve to direct the materials either into said chamber or said last mentioned spout.
